UNITED STATES PATENT OFFICE

131,935

DESIGN FOR A PLUMBER'S FURNACE

Joseph S. Fagan, Inglewood, Calif.

Application July 2, 1941, Serial No. 101,853

Term of patent 7 years

To all whom it may concern:

Be it known that I, Joseph S. Fagan, a citizen of the United States of America, residing at Inglewood, in the county of Los Angeles and State of California, have invented a new, original, and ornamental Design for Plumbers' Furnaces, of which the following is a specification, reference being had to the accompanying drawing, forming part thereof.

Fig. 1 is a side elevational view of a plumber's furnace, showing my new design.

Fig. 2 is a top plan view of the furnace.

Fig. 3 is a horizontal section taken on the line 3—3 of Fig. 1.

I claim:

The ornamental design for a plumber's furnace, as shown.

JOSEPH S. FAGAN.
